VARIABLE CONDENSER

Philip F. Scofield, Palo Alto, Calif., assignor to
 Heintz & Kaufman, Ltd., San Francisco, Calif.,
 a corporation of Nevada

Application October 4, 1932, Serial No. 636,230

2 Claims. (Cl. 74—428)

My invention relates to a variable condenser and, more particularly, to a condenser which is operated by a worm gear drive.

Among the objects of my invention are:

5 To provide a means for varying the capacity of large condensers:

To provide a worm gear for varying the capacity of a condenser:

To provide an irreversible gear drive for a variable condenser:

And to provide means for taking up back-lash in a worm gear drive for variable condensers.

Referring to the drawing, showing a preferred embodiment of my invention:

15 Figure 1 is an end elevation, and Figure 2 is a plan view thereof.

A pair of shafts 1—1 having condenser plates 2 mounted thereon, are positioned within a frame 3 in such a manner that when the shafts are rotated in frame bearings 4, the plates will interleave, varying from a full penetration to a complete separation.

Nuts 5 can be adjusted to space the interleaved plates properly, and to take up end play.

25 Fastened to each shaft, between the plates and frame, at one end of the condenser, is an insulating sector 6 of bakelite, lava or isolantite, or like material. These sectors carry, on their outer circumference, worm-gear sectors 7—7.

30 A lower worm bearing 8, indicated by dotted lines in Figure 1 and an upper worm bearing 9, position a worm shaft 10 preferably of bakelite rod, terminated at one end by a hand wheel 11, and carrying a worm 12 solidly applied to the rod 35 at a point where it will mesh with both of the gear sectors 7—7.

The worm is meshed with the sectors so that a continuous progression of the worm over the entire sector will vary the interleaving of condenser plates from zero to maximum. It is also desirable to have the gears so cut as to be irreversible, that is, so that the weight of the plates will not turn the worm in any position. This

saves counterbalancing of the plates and allows plates of heavy construction to be used, as is desirable in high powered radio transmitters.

To remove all back-lash, a tension spring 13 is attached to the upper angle of one sector by 60 an upper spring stud 14, and to the lower angle of the other sector by a lower spring stud 15.

The stress thus applied to the sectors causes the sectors to bear against opposite sides of the thread of the worm 12, with sufficient pressure to 65 eliminate backlash throughout the travel of the sectors. The opposing stresses cancel each other so that there is no additional thrust load placed on the worm shaft 10.

A worm drive as described will allow high gear 70 reductions, and the amount of interleaving, and capacity, can be changed in small increments, thus providing delicacy of adjustment. The drive is ideally adapted for extremely large capacitors, where the plates may reach the size of 12 by 12 75 inches, and the entire condenser made up of as many as 60 plates. The irreversibility of the gear readily takes care of the unbalanced weights.

I claim:

1. A drive adapted to interleave condenser 80 plates comprising a pair of shafts adapted to be rotated, on which said plates are mounted, a gear sector on each of said shafts, a common worm gear meshing with each of said sectors, and resilient means connecting said sectors for forcing 85 each of said sectors against said worm gear in opposite directions.

2. A drive adapted to interleave condenser plates comprising a pair of shafts adapted to be rotated, on which said plates are mounted, a gear sector on each of said shafts, a common worm gear meshing with each of said sectors, and a spring under tension connecting said sectors, said spring having one sector connection above the contact of worm and sector and the other sector connection below said contact. 95

PHILIP F. SCOFIELD.
